CLAIM

The ornamental design for a cantilevered container assembly, as shown and described.

DESCRIPTION

FIG. 1 is a front perspective view of the cantilevered container assembly of the instant invention;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.
